UNITED STATES PATENT OFFICE

FRITZ HERLACH, OF DUSSELDORF, GERMANY, ASSIGNOR TO RHEINISCHE METALL-WAAREN- UND MASCHINENFABRIK, OF DUSSELDORF, GERMANY, A CORPORATION OF GERMANY

FIREARM ARRANGED ON MOUNTING

Application filed August 21, 1929, Serial No. 387,509, and in Germany November 29, 1926.

My invention relates to fire arms arranged on mountings such as machine guns which are pointed by directly being turned by hand about its setting axis on the mounting. The invention consists in the fact that the handle that serves to point the arm is mounted thereon cardanically or at least so as to be turned about an axis extending parallel to the elevating axis (axis of the horizontal trunnions) of the arm. By this possibility of turning and thereby adjusting the handle a convenient natural position of the operator's hand which is grasping the handle is obtained without the hand closely grasping the handle, as required to hold the arm in the desired direction needs be loosened.

Our invention further provides in guns of this type in which also the trigger mechanism is operated by the operator's hand grasping the pointing handle to arrange also the trigger so as to be turned like the handle and to so interconnect these two members by suitable means that the trigger follows the pointing motions of the handle and thus is permanently in the range of the finger of the operator's hand operating the handle.

In order that our invention can be more easily understood, two preferred embodiments of the same are illustrated by way of example in the accompanying drawings as adapted to a machine gun mounted on a wheeled carriage and comprising an arrangement for varying the firing height.

In these drawings

Figure 1 is a lateral view of the gun and carriage in the position for high angle fire while

Figures 2 to 5 show on an enlarged scale the first embodiment of the pointing handle of the gun. More particularly

Figure 2 is a view toward the breech end of the gun,

Figure 3 is a section on line A—B of Figure 2,

Figure 4 is a section on line C—D of Figure 2, while

Figure 5 is a section on line E—F of Figure 2.

Figure 6 is a rear view of the other embodiment,

Figure 7 is a corresponding longitudinal section seen from the top, while

Figure 8 is a section on line G—H of Figure 7.

Referring first to Figure 1, A denotes the gun barrel the casing A₁ of which is mounted for elevation about the axis A₂ of the horizontal trunnions in an intermediate carrier Z. The latter rests on a platform the trail of the wheeled carriage U subsides into and can be fixed thereon in a horizontal position for long range fire and in a vertical position for high angle fire as illustrated. On the rear end of casing A₁ is arranged the pointing handle B (shown only diagrammatically) which is mounted thereon so as to turn about an axis B₁ parallel to that of the horizontal trunnions A₂. The construction of handle B will be described hereinafter.

As seen from Figure 2, the rear wall a of the breech end has swingingly mounted thereon by means of eyes a₁, a₂ and two pins b₃ the manipulating piece b that possesses two handles b₁, b₂, the pins b₃ extending parallel to the axis of the horizontal trunnions, Figure 5. In the range of the fingers of the operator's hands grasping the two handles b₁, b₂ are arranged two triggers c₁, c₂ the one of which is intended to cause single fire and the other continuous fire. The triggers c₁, c₂ are so connected to the firing device lodged in the breech end a and comprising a lever d and a rod d₁ by levers c₃ and links c₄ that no mutual displacement of the parts of the firing device can take place upon the handles b₁ being turned. To this end the fulcrum of link c₄ on lever d coincides with the turning axis of the manipulating piece b.

In order to prevent the manipulating piece b from being turned as described relatively to the breech end a of the arm, the eyes a₁, a₂ on their periphery have recesses a₃ adapted to be engaged by locking bolts e of piece b. These bolts e can be disengaged from the recesses a₃ by means of a releasing piece f which is in the range of the thumbs of the operator's hands grasping the handles b₁, b₂ and can be shifted inward in the piece b against the action of a spring f₁. Two double levers g₁, g₂ pivoted on pins g₃, g₄ in the

piece *b* engage both the releasing piece *f* and the locking bolts *e*, Figure 5. When the releasing piece *f* is shifted inward by thumb pressure the locking bolts *e* are lifted from the recesses *a*₃ so that the piece *b* then can be turned about the pins *b*₃ relatively to the gun. Upon releasing piece *f*, it moves outward under the action of spring *f*₁ and the bolts *e* enter those of the recesses *a*₃ of the eyes *a*₁, *a*₂ that are opposite to them according to the position piece *b* just assumes.

In this manner the gun and the manipulating piece *b* can be coupled with one another during the pointing motions whereupon after the gun has been set to the desired firing direction the piece *b* is given a position enabling convenient and close grasping of the handles *b*₁, *b*₂ during firing by temporarily releasing the described locking device.

In the embodiment illustrated in Figures 6 to 8 the breech end *a* carries two lateral hollow extensions *a*₄ extending in parallel to the axis of the horizontal trunnions on which extensions the two pointing handles *b*₁, *b*₂ are arranged rotatably and are secured against being withdrawn from the extensions in any suitable manner. A trigger *c*₁, *c*₂, respectively, is pivoted on each of the handles *b*₁, *b*₂ in such a manner that it can be reached by the fingers of the operator's hand grasping the respective handle. Out of the triggers that denoted by *c*₁ is intended for single fire while *c*₂ serves to cause continuous fire. As shown in Figure 7, the triggers *c*₁, *c*₂ project with suitable noses into the bores of the extensions *a*₄ which noses abut on a trigger rod *c* shiftably mounted in the extensions and acted upon by a spring. This rod by means of an inclined surface *c*₅, Figure 6 acts upon a lever *d* and by the latter on the locking mechanism of the hammer (not shown).

When the gun is held by the hands and is swung about its horizontal trunnions relatively to the mounting by grasping the handles *b*₁, *b*₂ the latter turn about the extensions *a*₄. The triggers *c*₁, *c*₂ take part in this turning motion and are maintained in their position relatively to the handles without losing their connection with the other members of the firing mechanism or displacing them. The close grasping of the handles *b*₁, *b*₂ required for holding and pointing the arm therefore neither needs be changed in giving even comparatively great elevations nor need be loosened in laying a finger on one of the two triggers *c*₁, *c*₂.

What I claim and desire to secure by Letters Patent is:—

1. A fire arm comprising a mounting and a gun supported by it and adapted to be swung by hand about its pointing axes relatively to the mounting, and at least one pointing handle on said gun, said handle being

adapted to be turned relatively to the gun at least about an axis parallel to the elevating axis of the gun.

2. A fire arm comprising a mounting and a gun supported by it and adapted to be 70 swung by hand about its pointing axes relatively to the mounting, at least one pointing handle on said gun adapted to be turned relatively to the gun at least about an axis parallel to the elevating axis of the gun, a 75 trigger mechanism to be operated by the hand manipulating said handle, the trigger of said mechanism being adapted to be turned relatively to the gun about an axis analogous to that of said handle, and means interconnecting said handle and trigger and causing the latter to follow the pointing motions of said handle. 80

3. A fire arm comprising a mounting and a gun supported by it and adapted to be 85 swung by hand about its pointing axes relatively to the mounting, at least one pointing handle on said gun adapted to be turned relatively to the gun at least about an axis parallel to the elevating axis of the gun, and means 90 for temporarily rigidly connecting said handle to said gun at least in one of their mutual positions. 95

4. A fire arm comprising a mounting and a gun supported by it and adapted to be 100 swung by hand about its pointing axes relatively to the mounting, at least one pointing handle on said gun adapted to be turned relatively to the gun at least about an axis parallel to the elevating axis of the gun, a trigger mechanism to be operated by the hand manipulating said handle, the trigger of said mechanism being adapted to be turned relatively to the gun about an axis analogous to that of said handle, means interconnecting said handle and trigger and causing the latter to follow the pointing motions of said handle, and means for temporarily rigidly connecting said handle to said gun at least 105 in one of their mutual positions. 110

5. A fire arm comprising a mounting and a gun supported by it and adapted to be 115 swung by hand about its pointing axes relatively to the mounting, at least one pointing handle on said gun adapted to be turned relatively to the gun at least about an axis parallel to the elevating axis of the gun, a trigger mechanism to be operated by the hand manipulating said handle, the trigger of said mechanism being adapted to be turned relatively to the gun about an axis analogous to that of said handle, means interconnecting said handle and trigger and causing said trigger to follow the pointing motions of said handle, and means for temporarily rigidly 120 connecting said handle to said gun at least in one of their mutual positions, said last-named means comprising a manipulative member arranged in the range of the hand operating said handle. 125 130

6. A fire arm comprising a mounting and a gun supported by it and adapted to be swung by hand about its pointing axes relatively to the mounting, at least one pointing handle on said gun adapted to be turned relatively to the latter at least about an axis parallel to the elevating axis of the gun, a trigger mechanism on said gun adapted to be operated by the hand manipulating said handle and comprising at least one trigger, at least one journal on the gun, said handle being rotatably mounted on said journal and said trigger being rotatably mounted on said handle.

15 In testimony whereof I have affixed my signature.
